UNITED STATES PATENT OFFICE.

JOHN A. McFERRAN AND MILTON L. McFERRAN, OF LOUISVILLE, KENTUCKY.

DRAFT-REGULATOR AND SMOKE-PURIFIER.

1,292,834.

Specification of Letters Patent. Patented Jan. 28, 1919.

Application filed July 23, 1917. Serial No. 182,376.

To all whom it may concern:

Be it known that we, JOHN A. McFERRAN and MILTON L. McFERRAN, citizens of the United States, residing at Louisville, in the 5 county of Jefferson and the State of Kentucky, have invented certain new and useful Improvements in Draft-Regulators and Smoke-Purifiers; and we do hereby declare the following to be a full and exact description of the invention, such as will enable 10 others skilled in the art to which it appertains to make, install, and use the same.

This invention of ours relates to draft-regulators and smoke-purifiers for coal-burning steam boilers, and is an improvement 15 on our invention set forth in Letters Patent No. 1,142,721 granted us June 8, 1915, which had for its principal objects the increasing of combustion of fuel in the fire-box of a steam engine with the view of eliminating the smoke therefrom and of economizing in use of fuel.

At the time said Letters Patent were applied for, four ordinary flues through the 25 boiler connected to a cross pipe in the smoke-box, as shown, were thought to be ample to carry sufficient air to the fire-box for perfect combustion, but in the light of subsequent experiments it has been found desirable to 30 provide more than this number of flues.

Therefore the present invention contemplates the provision of an improved construction whereby an ample supply of air may be conducted directly to the point of 35 greatest efficiency while at the same time the tubes are protected from the heat, and burning out of the same is avoided.

This present invention, like our other said invention, has for its objects (1) to increase 40 the efficiency of the fire in the furnace of a steam boiler by the introduction of an unusual quantity of oxygen or air into the fire-box. (2) to consume the smoke and cinders in the fire-box and thus prevent them from 45 passing through the flues and stack, and (3) to economize in the fuel.

All of these objects are attained in the present invention and the draft-regulating and smoke-purifying devices illustrated in 50 the accompanying drawings which form a part of this specification, are practicable and embody novel and useful details of construction, arrangement and combination of parts, all of which will be described at length 55 with reference to said drawings, and will

be definitely pointed out in the claims that follow the description.

In said drawings, Figure 1 is a longitudinal vertical section of a locomotive boiler.

Fig. 2 is a transverse section through the 60 smoke-box, parts being shown in elevation.

Fig. 3 is a cross-section of a locomotive boiler made through the fire-box in a plane near the back flue-sheet, showing the arch 65 in section.

Fig. 4 is a side elevation of some of the mechanism in the smoke-box.

We have shown our invention in connection with a locomotive boiler but it should be understood that the invention may be applied to any form of boiler, whether stationary or not.

Referring to the drawings, the letter M designates a locomotive boiler and G its smoke-box. A designates a hollow casting 75 which we call the manifold used as a header for the plurality of inclosed boiler flues C. The back section A' of this manifold A is made in the size and shape, see Figs. 2 and 4, to fit snugly on over the inclosed flues C 80 and to follow the sheet web between the flues and around the inclosed flues C.

To install this invention on a boiler we remove as many old flues from the boiler as we have decided to inclose with our manifold A, possibly 15 or 16, in number, and then set in new flues C adapted to stand out two or three inches beyond the flue-sheet K, inside the smoke-box, as shown in Figs. 1 and 4, to help support the manifold casting 90 A in its operative position on the flue sheet K. Iron straps I, provided with bent ends I' are held in position by the bolts N' which hold exhaust nozzle N in position. These bolts are tightened after the straps I have 95 been swung to such position as to forcibly and resiliently engage the manifold A and hold said manifold in place against flue sheet K.

The arch D, Figs. 1 and 2, forms an air-tight connection with the contacting flue-sheet H and the side sheets of fire-box X so that all gases of combustion have to travel upward over the high end of arch D to pass through the flues C' and through the stack 105 Z. C'' represents all flues that are wholly or partially stopped by the arch D.

In Figs. 1 and 2 may be seen longitudinal sections of exhaust nozzle N through planes at right-angles to each other, showing dif- 110

ferent views of the nozzle partition V and of the exhaust ducts leading to the stack Z. On the upper end of nozzle N is mounted blower ring F' provided with blower jet E and blower pipe F which is the ordinary locomotive blower pipe admitting steam to the blower ring at the option of an operator in the cab. J represents the petticoat section of the smoke stack flaring out over the 10 nozzle N to equalize the draft.

In Fig. 1, the descending draft sheet is indicated by the letter R and P is the horizontal draft sheet, while O is the cinder sieve, and L is a baffle plate at the lower end 15 of said sieve. Some of these parts are represented to show the relative positions of parts of our invention.

B, B', B^x and B^{x'} are four intake pipes leading through the front casting T of the 20 smoke-box G downward and backward through smoke-box G and into manifold casting A. In Fig. 1 intake pipes B' and B^{x'} are omitted for the sake of clearness of outline in the drawings; but they are shown 25 in Fig. 2 in their relative normal positions. Pipes B^x and B^{x'} enter casting A at the front and pipes B and B' enter said casting A on either side.

Now it is evident that when the engine is 30 working exhaust steam from the cylinders passing out through nozzle N and stack Z, tends to create a vacuum in smoke-box G, thus starting a draft through flues C' from fire-box X; and when the engine is not working, the smoke-box blower may be turned on so that the steam from the boiler rushing through pipe F, blower ring F' and jets E upward through stack Z, also causes a tendency toward a vacuum in smoke-box G, 35 starting a draft through flues C' from the fire-box. This draft in either case takes with it from the fire-box gases, smoke and cinders. Therefore, if combustion is not complete in the fire-box, the partially burned 40 gases, and cinders will pass off through the flues C', smoke-box G, petticoat J and stack Z to the atmosphere, taking along with them sparks and black smoke. For combustion cannot readily take place after the gases 45 enter the flues; and smoke once formed does not readily burn in the ordinary fire-box. But with our smoke-purifying device the smoke is either consumed or prevented from forming in the furnace.

50 One important feature of our invention, therefore, consists of improved means for taking fresh air in at the front of the engine through the intake pipes B, B', B^x and B^{x'}, Fig. 2, where it is heated by interior radiation of said intake pipes in the hot smoke-box as it passes through to the manifold casting and thence through the inclosed flues C, on its way to fill the partial vacuum created by the draft through the fire-box X, 55 under brick arch D. This air is of such a

quantity, quality and temperature, when it enters the fire-box X, that it unites readily with the gases liberated from the burning fuel; and its thorough mingling with these gases in its long travel under and over arch 70 D to flue sheet H, insures ample combustion to prevent smoke and sparks from issuing from stack Z. Furthermore the temperature of fire-box X is maintained more nearly uniform, a fact which reduces the expansion 75 and contraction of the fire-box sheets and flues. Also more heat is secured from the fuel, and the engine is more readily kept at its maximum efficiency, than is the case without our invention.

Having described our invention, what we claim is:-

1. In a draft-regulator and smoke-purifier for locomotives, the combination with a smoke-box and a fire box of a flue-sheet at 85 the back of the smoke-box, a plurality of flue-tubes reaching from the smoke-box to the fire-box and having their front ends standing out beyond said flue-sheet into the smoke-box, a manifold casting used as a 90 header for said plurality of flue-tubes and having a reduced section at its back left open and fitting closely on over the outstanding ends of said plurality of flue-tubes to hold said manifold from lateral movement on said flue-sheet, resilient means bearing against the front of said manifold to hold it securely against said flue-sheet, with a series of intake tubes leading from the open air through the smoke-box into said 100 manifold casting.

2. In a draft regulator, in combination, a steam boiler having a fire box and a smoke box, a flue sheet forming the front wall of the fire box and a flue sheet forming the rear 105 wall of the smoke box, a series of tubes leading through the flue sheets and connecting the fire box with the smoke box said tubes serving as flues for the products of combustion, an arch spanning the fire box and having its front edge disposed in contact with the flue sheet at the front end of the fire box, a second series of tubes extending through the flue sheets, a manifold casting 110 inclosing the forward ends of said latter tubes within the smoke box and acting as a header for said tubes, a plurality of intake pipes leading from the atmosphere to said manifold casting and a brace having a resilient end which resiliently presses said casting against the flue sheet at the rear of the smoke box.

3. In a draft-regulator and smoke-purifier, the combination of a fire-box having an air-tight brick arch to aid combustion, with 125 a hot chamber or smoke-box having a stack and an exhaust nozzle provided with a steam blower to regulate the draft therein, a manifold casting, means for resiliently pressing said casting against the flue-sheet of said 130

smoke-box, one or more air tubes leading from the open air through the smoke-box into said manifold, and a series of hot-air tubes running from said manifold back 5 through the boiler to the fire-box to carry the heated air or oxygen to the fire-bed beneath the said arch and thus aid combustion therein, as described.

4. A steam boiler construction for locomotives comprising a fire box, a smoke box, a flue sheet at the front of the fire box, a flue sheet at the rear of the smoke box, a stack leading from the top of the smoke box, an exhaust nozzle in the smoke box there- 10 beneath, an arch spanning the fire box and having tight connection with the flue sheet at the front of the fire box, a plurality of flues passing through the flue sheets above the arch and serving as flues to conduct the 15 products of combustion from the fire box to the smoke box, a second series of flues extending through the flue sheets below the arch, a manifold having an open back, intake pipes leading from the atmosphere to 20 the manifold and pressure exerting means disposed between the exhaust nozzle and the manifold and serving to press the open back of the manifold against the flue sheet at the 25 rear of the smoke box to thereby inclose the area occupied by the forward ends of the 30

last named series of tubes, the latter serving to conduct air from the manifold to the space beneath said arch.

5. In a draft regulator and smoke consumer for locomotives, the combination with 35 a smoke box and a fire box, of a flue sheet at the rear of the smoke box, a plurality of flue tubes extending from the smoke box to the fire box and having their front ends standing out beyond the flue sheet into the 40 smoke box, a manifold constituting a header for said plurality of flue tubes having an open back and fitting closely on over the outstanding ends of said plurality of flue tubes to hold the manifold against lateral movement on the flue sheet, means bearing against the front of the manifold to hold it securely against said flue sheet, and means for conducting air leading from the atmosphere 45 through the front of the smoke box and into 50 said manifold.

In testimony whereof, we have hereunto set our signatures in the presence of two witnesses.

JOHN A. McFERRAN.
